(57) **CLAIM**

The ornamental design for a control panel housing frame, as shown and described herein.

DESCRIPTION

FIG. 1 is a front view of a control panel housing frame showing our new design.

FIG. 2 is a rear view thereof.

FIG. 3 is a top view thereof.

FIG. 4 is a bottom view thereof.

FIG. 5 is a left side view thereof.

FIG. 6 is a right side view thereof; and,

FIG. 7 is a perspective view thereof.

Those portions of the control panel housing frame shown in broken lines are included for illustrative purposes only and form no part of the claimed design.

1 Claim, 7 Drawing Sheets
